Primary Examiner — Philip S Hyder*Assistant Examiner* — Keith Frank*(74) Attorney, Agent, or Firm* — James T. Fondriest(57) **CLAIM**

The ornamental design for a foam dispenser, as shown and described.

DESCRIPTION

FIG. 1 is a front perspective view of a foam dispenser showing our new design;

FIG. 2 is a rear elevational view thereof;

FIG. 3 is a front elevational view thereof;

FIG. 4 is a bottom plan view thereof;

FIG. 5 is a top plan view thereof;

FIG. 6 is a left side elevational view thereof; and,

FIG. 7 is a right side elevational view thereof.

The Dash Dot Dash broken line(s) which define the bounds of the claimed design form no part thereof.

In the drawings, the Dash Dash broken lines depict unclaimed portions of the foam dispenser and form no part of the claimed design.
